(57) **CLAIM**

The ornamental design for a product holding container, as shown and described.

DESCRIPTION

FIG. 1 is a perspective view of the product holding container showing our new design;

FIG. 2 is a side elevational view thereof, each of the sides being identical in appearance; and,

FIG. 3 is a top plan view thereof.

The bottom surface of the design is disclaimed.

1 Claim, 3 Drawing Sheets

FIG.

FIG. 2

FIG. 3
